METHOD AND APPARATUS FOR BELLOWS POCKETS

Albert H. Weis, Nyack, N. Y., assignor to Willcox & Gibbs Sewing Machine Co., New York, N. Y., a corporation of New York

Application July 31, 1936, Serial No. 93,669

9 Claims. (Cl. 112—136)

This invention relates to improvements in methods and apparatus for advantageously stitching a strip or strips to a body, and to an improved form of edging or strip.

5 In its present most useful form it relates to a special structure on a sewing machine, adapted to open, fold, and guide a prefolded bellows strip relative to a body, and to stitch the so-conditioned strip and body together.

10 Heretofore, it has been possible to make so-called bellows pockets, which are capable of lying close to the main body of a coat when empty or nearly so and of moving into an extended position when filled, only by a plurality of awkward 15 hand operations with ununiform results.

It is an important object of the present invention to provide a method and apparatus for producing bellows pockets, ready for assembly to a garment, economically and uniformly in a single 20 operation.

25 In the manufacture of modern clothing, there is a demand for a bellows pocket that can be stitched to the garment with concealed stitches, so that no stitches will show on the outside of the coat, or other garment to which the pocket is applied. Heretofore, only overcoats, top coats, and sack coats, and especially sportswear of expensive type, have been provided with this bellows pocket since it could not previously be produced on a production or inexpensive basis, even though this advanced tailored finish of bellows pockets presents a very neat appearance, leaving suitable space for pocketed articles, without effecting the usual bulged or bulky appearance to 30 the outside of the garment. To accomplish this, the pocket material is not secured to the garment itself, but through the medium of a bellows bias or elastic strip which is folded upon itself so as to collapse and expand similar to an accordion 35 pleat or fold when the pocket is put to use.

40 According to the method in general use, prior to the present invention, this is accomplished, by first, stitching a strip to one side of the pocket material along the right angle edges and around one corner thereof joining these edges. Then by folding the strip over on the other face of the pocket material, it was again stitched down with a second sewing operation, thus producing two 45 lines of stitching. This method was costly and it was difficult to maintain uniformity in the spacing of the stitch lines relative to one another and relative to the form or pattern of pocket or the like. Then in another operation, the strip of material stitched to the pocket was folded back upon itself, ready for the stitching of the

5 pocket to the garment. This third stitching operation was often done by hand with needle and thread to effect concealed stitching, to prevent any stitches from showing on the outside of the garment, or in some instances was accomplished with an invisible or blind stitch machine, turning the raw edge as the stitching proceeds, while it is guided to the stitching instrumentalities. Bellows pockets made in this manner and method require great skill in the tailoring trade, and as 10 a result thereof, have been only used on the more expensive garments.

15 With the present invention, it is now possible to apply this modern and desirable bellows pocket to the lower or popular priced line of garments; since manufacture can be accomplished uniformly by inexperienced operators, and a large production is possible a few hours after the improved process and apparatus of the present invention is put into use.

20 Broadly, this is accomplished by providing the well-known Metropolitan machine, or the like, having two needles and two loopers and a suitable feeding mechanism designed and arranged to feed the work from the stitching instrumentalities so as to feed along straight lines as well as around curves or rounded corners, and smoothly lay a bias cut or elastic strip of material 25 over and around the raw edge of the pocket, leaving an extension and folded portion underneath of sufficient width to permit the pocket to be attached to clothing with a subsequent 30 stitching operation whereby all of the stitches are concealed except the two lines of needle threads shown on the top of the work, one line of which 35 passes through the folded marginal section of the strip and the other line a suitable distance therefrom in parallel relation. By selecting threads which match the materials, these two lines of stitching scarcely show. When they match the 40 materials, they are inconspicuous so that when the bellows pocket is sewn to the inside of a coat, a neat and slight finish so much desired by the clothing manufacturers is produced, making the garments more attractive and saleable.

45 Heretofore, production of bellows pockets was so costly that it was cheaper to provide linings to the front sections of coats to cover up and hide the pockets, some of which were made of canvas and other strong materials, hanging loose on the 50 inside of the coat between the outside fabric and the lining, but with the present improvements in the manufacture of bellows pockets, skeleton coats without lining can now be produced economically and neatly for all grades of clothing.

In the old method of producing bellows pockets for clothing, special careful folding of the bias strip was necessary during or subsequent to the individual stitching operations in order to conceal the rough edges of the bias strip or to form a connector section in the strip for neat final uniting of the bellows pocket to the body of the garment, all of which called for the use of expensive highly skilled labor and even then resulted in an ununiform product.

In this connection, also, it was desirable and great care was necessarily exercised to have the margin of the connector section of the strip end short of or inside the perimetric section of the pocket body to be fully concealed thereby after final assembly.

It is an important object of the present invention to provide a prefolded bellows strip in which the marginal edges are prefolded to be automatically concealed during the regular stitching operation, and in which the operator need not manually fold a connector section from the base of the strip or in which there is danger of an irregular and unsatisfactory final appearance.

A feature resulting from the attainment of this object is the provision of a prefolded bellows strip, which makes possible a neat and absolutely uniform result, for pockets and other articles, in which a connector and a base section are preformed so that the former is uniformly shorter and concealed by the latter and in which with one form one or both of these sections are provided with preformed marginal fold; and in another modified form the bellows strip is of two-piece structure differing from the other mainly in the provision of a separate binder or edging strip to envelop the other edge of the base section and edge of the body to which the bellows strip is applied.

One of the most important objects of the present invention is the provision of an improved method of manufacturing pockets and other articles with a bellows strip in which the several operations now usually performed by expensive and highly skilled workers may be reduced to a single inexpensive operation which may be performed by comparatively unskilled workers, and which will result in a highly satisfactory and uniform product.

A feature of the present invention is the achievement of this desideratum.

Another important object of the present invention is the provision of apparatus to advantageously carry out the method of the present invention, whereby prefolded strips may be opened, lapped, and otherwise handled and guided with accuracy, relative to the body of an article to which it is desired that it be secured and even though there is a decided tendency of the prefolded strip to always assume its original pressed or formed position; to accurately guide and lap an edge portion of the strip around the edge of the article, and to maintain the marginal edge of the connector section of the strip within or inside the marginal edge of the article.

Features resulting from the accomplishment of this object are the provision of an opening, folding, and guiding mechanism which may be easily and quickly secured in operative position on the sewing machine or removed therefrom to expose fully the looper and other under operating mechanism; accurately guides a body or main ply toward the sewing mechanism; opens superposed base and connector sections of a bellows strip without wrinkling; laps an edge of the bellows strip around an edge of the body uniformly;

guides the associated body with the opened and lapped bellows strip in a straight line to the sewing mechanism where they may be sewed together by a line of stitching passing through the lapped portion of the bellows strip near the outer edge of the body and/or by a line of stitching passing through the base section near the crease line forming the superposed and integral connector section so that the latter line of stitching will be concealed by the connector section when the latter again assumes its folded or formed position. Most of these structural features are likewise embodied in a slightly modified form of mechanism for applying a two-piece bellows strip edging to the body of a pocket, or other article.

The characteristic features and advantages of my improvements will appear more fully from the following description and accompanying drawings illustrating the present preferred embodiments of my invention, in which:

Fig. 1 is a top view showing part of a sewing machine work plate, feeding and stitching instrumentalities, with the improved guiding and folding attachment of the present invention.

Fig. 11 is a fragmentary view of a garment section made with the modified form of the invention shown in Fig. 10.

Before describing in detail the improved method and apparatus provided by the present invention, and in order to facilitate an understanding thereof, it is desirable to describe a novel bellows strip 12 which forms an important part of the present invention and greatly facilitates the economical and uniform production of bellows pockets and the like. This bellows strip is preferably made of bias or elastic fabric, in strip form, which in its initial stage is substantially as shown in the fragmentary sectional view 8A. During the course of preparing the bellows strip the rough or outer edges 12a and 12b of the strip are folded back onto one face of the strip to provide marginal sections 13 and 14. Also, the strip is provided with an off-center fold or crease 17 spaced between the marginal sections 13 and 14 to divide the strip 12 into an integral connector section 15 and base section 16 as shown in the fragmentary sectional views 8C and 8D with the connector and base sections preferably in superposed relation. Preferably the marginal section 14 of the base

section 16 is offset or spaced from the marginal section 13 of the connector section 15 to provide material for lapping the marginal section 14 around an edge of a body, and so that when the latter is accomplished the marginal sections 13 and 14 will be closely adjacent to each other.

Referring particularly to Figs. 1 through 9 inclusive, a now preferred form of the attachment 18 will be described in detail first. The main function of this attachment, the structural details of which are about to be described, is to guide the prefolded bellows strip 12 and an edge 19 of a body 20, such as the main section of a pocket 21, to a sewing mechanism 22, and to currently open, guide, and sew the prefolded bellows strip 12 to the body 20 in a very accurate and particular relation. To this end it opens the strip 12 so that a superposed connector section 15 will not be sewed to a base section 16 thereof and at the same time laps the marginal section 14 of the strip around the edge 19 of the body, as the body 20 and strip 12 approach the sewing mechanism 22 whereupon the lapped and base sections may be sewed to the body.

A complete showing and detailed description of the sewing machine is deemed unnecessary, since the present invention is applicable to various sewing machines now in the field. For the purpose of illustration it is shown as applied to the well-known Metropolitan machines, for example, as more completely shown in the U. S. Patent No. 1,344,284, granted June 22, 1920.

Briefly, for illustrating the present invention, there is shown a sewing machine consisting of a base 23, having an overhanging arm and head 24, in which is operated the sewing mechanism including a needle bar 25 in the usual manner, carrying needles 26 and 27. A presser foot 28 cooperates with a feed dog 29 operating through openings 29' in a throat plate 30 carried by a cloth plate 31 secured to lugs 32 of the base 23 of the machine. Operation of the feed dog 29 is effected by any of the now well-known feed dog driving mechanisms. Cooperating with the needles 26 and 27 in the now well-known manner to form stitches are loopers 26a and 27a carried by looper mechanism 38 to complete the sewing mechanism 22 which may be of any well-known type.

While the improvements are shown applied to a Metropolitan two needle double thread chain stitch machine, the invention is not limited to two needle stitching or to chain stitch machines. It can be used with other types of machines as well. The needles 26 and 27 operate through needle holes 26b and 27b in the throat plate 30 which supports the materials during the stitching operation. Preferably the throat plate 30 is provided with a cut-out 33 close to the stitching position to conveniently accommodate a detachable and removable base plate 34 that may closely fit against an edge 33'. This base plate has extensions 35 resting upon lips 36 of the cloth plate 31 so that the base plate is supported 65 flush with the top surface of the cloth plate 31 and the throat plate 30, leaving a smooth surface over which the work is fed. This base plate 34 is secured in place by thumb screws 37 or by providing spring clips, to prevent shifting there- 70 of during the operation of the machine. Because the base plate is of the shape and form illustrated it is very convenient for threading, cleaning, adjusting, and oiling of the machine, since when it is removed, the entire stitching and feed- 75 ing instrumentalities are made accessible. Also,

fingers can be used for threading the loopers without the use of tweezers or other instruments and this proves a great convenience and economy during use of the machine. Moreover, it permits the removal of the attachment as often as required; and, its replacement in exact registration with the stitching and feeding instrumentalities is insured. This is especially useful in connection with machines employing loopers and looper threads or in the vertical hook type of machine employing bobbins for making the well-known lockstitch, since it is necessary or desirable to have free access to the bobbins each time the bobbin thread is exhausted.

Coming now to the structural details of the attachment 18; in its present preferred form the attachment comprises an edge guide plate 40 secured to the base plate 34 by a screw and slot connection 41 including elongated slots 41a and screws 41b. Preferably the guide 40 is provided with a projection 42 extending beyond the base plate 34 and over the throat plate 30 into a position adjacent and parallel the presser foot 28.

As may be seen best in Fig. 4 the attachment 18 includes a main guide 43 for opening, guiding and lapping the bellows strip 12. Although this main guide 43 may be constructed in various ways it is now preferably made with an extension 43a projecting to a point remote from the base plate 34 and at a right angle thereto which at its outer extremity is provided with a channel 43b for initially opening and flattening the bellows strip 12 from the superposed condition shown in Fig. 8D to the condition shown in Fig. 8C. Although the extension 43a is shown constructed to feed the strip 12 from a right-hand side, reverse it and cause it to pass through a right angle path, this is not essential. The reel or roll of strip may be placed underneath the table and fed up from the supply directly to the 35 folder.

Overlying the base plate 34 the main guide 43 is provided with an integral flat channel 43c and contiguous upwardly curled channel 43h of substantially flattened tubular shape, joined integrally with the extension 43a by a loop section 43d having fingers 43f and 43g to maintain the strip in registry therewith during travel.

The flat channel 43c includes top and bottom walls 43i and 43j respectively adapted to confine 50 an adjustable marginal guide 44 preferably having a plate 45 of bent metal with yawning edges secured thereto as by soldering. This adjustable marginal guide 44 is secured in any desired position laterally relative to the upwardly curled 55 channel 43h by suitable screws 46, threaded therein and passed through elongated slots 47 in the top wall 43i. The upwardly curled channel 43h accommodates the marginal section 14 of the strip 12 and the adjustable marginal guide 44 accommodates the marginal section 13. Adjustment of the marginal guide 44, with the structure just described, makes it possible for the one attachment 18, and main guide 43 thereof, to accommodate bellows strips 12 of various 60 widths, and insures a location of the marginal section 14 fully in the upwardly curled channel 43h.

The main guide 43 is preferably secured to the guide plate 40 by riveting, soldering or the like 70 so that it may be shifted, located and held on the base plate 34 in various lateral positions by the screw and slot connection 41.

The adjustable marginal guide 44 may be of one-piece construction as shown in Fig. 9 having 75

an integral V channel 44a as apparent in this figure. The screws 46 are threaded into the marginal guide in order to lock the plate in position, this end being achieved when the heads of the screws are drawn into engagement with the upper face of the top wall 43i.

An inner curled wall 48 on the channel 43h accommodates the edge 19 of the body 20 or the like, as may be seen best in Figs. 3 and 4. Thus, the top wall 43i may serve as a table for the body 20 and the inner curled wall 48 will guide the edge 19 of the body into predetermined relationship with the marginal section 14 as it issues from the curled channel 43h. However, to provide additional larger table service for the body 20 to insure a smooth and easy travel thereof into the attachment 18 an extension plate 49 is provided. This extension plate may be welded, soldered, or otherwise secured to the top wall 43i and it is preferably provided with elongated slots 47 adapted to clear the heads of the screws 46 so that the latter will not interfere with the free passage of the body.

Preferably a top plate 50, overlying the curled channel 43h and the body 20 at the curled wall 48 is provided to assist in guiding the edge 19 to the curled wall 48 and to keep the body flat on the extension plate 49 and/or on the table formed by the top wall 43i.

With the structure in the attachment 18 so far described it is possible to accurately guide the body 20 and to concurrently open, guide and lap a bellows strip 12 relative to the body 20, so that the two may be accurately directed to a sewing mechanism 22 to be stitched together.

However, the attachment provides additional mechanism to prevent the bellows strip 12 from puckering, to insure a straight line travel thereof and to neatly fold or lap the marginal section 14 completely around the edge 19 of the body 20 and down flat onto the face of the body. It accomplishes this desideratum at a point in very close proximity with the presser foot 28 and feed dog 29, and with the sewing mechanism 22, so that there is no danger of the strip and body moving out of desired predetermined relationship.

This auxiliary mechanism greatly improves the product and insures a uniform result. It includes the provision of a cut-out 52 in at least the top wall 43i, and if desired the bottom wall 43j, adapted to accommodate a yielding main finger 53. If desired this main finger 53 may be formed from the top wall 43i when the cut-out 52 is made. However, it is preferable to have it in the form of a separate piece soldered or secured by rivets 54 to the top wall 43i. This finger is flexed or bent toward the base plate 34 to maintain the strip 12 in the flattened condition shown in Fig. 8C.

If preferred, and in order to insure a longer flexing life to the main finger 53 it may be provided with an integral looped over extension 54 forming a secondary finger 55 pressing down upon the main finger 53. The relation of the finger 53 (and 55) to the opened strip 12 and body 20 is clearly shown in Fig. 3. While the finger 53 may fully overlie the crease 17, it is preferably directly adjacent thereto as shown.

A complementary structure to insure a uniform product includes the provision of a yielding finger 57 adapted to receive the marginal section 14 after the latter is folded or lapped around the outer edge 19 of the body 20, to accurately lay the marginal section inwardly a predetermined extent from the edge 19 and flat upon the top face of the body 20 as shown in Fig. 3.

The finger 57 yieldingly accommodates itself, and the marginal section 14 which it carries, to divers thicknesses of body 20. The finger 57 is provided with a return loop 57' as is clearly apparent in Fig. 5. The latter figure clearly illustrates the relationship of the body 20 and the strip 12 and clearly shows the relationship of the adjustable marginal guide 44, main finger 53, and the yielding finger 57.

As with the finger 53 the finger 57 may be formed from the top curled section 43h or may be in the form of a separate strip soldered or otherwise secured thereto.

The method of the present invention includes the steps of: opening the bellows strip 12 so that the connector section 15 is no longer superposed upon the base section; concurrently feeding body and strip, such as 20 and 12; lapping a marginal section 14 of the strip 12 around the edge 19 of the body 20; flattening and guiding 20 the strip relative to the body; and sewing the strip and body together by the line of stitching 60 and/or 61.

During the performance of this method, and according to the structure provided by the present invention, the channel 43b opens the superposed sections of the bellows strip 12 and the flat channel 43c guides the open strip in a straight line toward the sewing mechanism 22. Concurrently the yielding finger 53 (and 55) presses the strip 12 flat and assists in guiding the strip in a straight line while at the same time preventing the strip from puckering. The body 20 is moved across the top wall 43i and plate 49 until the edge 19 engages and is guided by the curled inner wall 48, so that the edge 19 travels in the same straight line as the strip 12. As the strip 12 and body 20 are moved in a straight line toward the sewing mechanism the upwardly curled channel 43h and channel 58 carried by the yielding finger 57 serve to lap the marginal section 14 of the strip 12 around the edge 19 of the body 20 to a point very close to the needles 26 and 27. As the body 20 and strip 12 issue from the attachment 18 the lapped marginal section 14 is secured around the edge 19 and to both faces of the body 20 by a line of stitches 60 formed by the needle 27 and looper 21a.

At the same time the base section 16 may be sewed to the body 20 at a marginally spaced point 50 preferably immediately adjacent the crease 17 with a second line of stitching 61 formed by the needle 26 and looper 26a. Both of these lines of stitching may be used to secure the strip 12 to the body 20 or the line of stitching 60 alone may be used. Great economies, and a product free from puckering results from sewing both lines of stitching at the one time, and while the strip 12 is laid out accurately by the fingers 53 and 57.

From the foregoing it is apparent that the present invention provides a method of forming a bellows pocket 21 or the like, complete and ready for attachment to the main body of the garment all in a single handling, and in a manner to insure an economical and uniformed product.

Figs. 10 and 11 disclose a modified form of the present invention for applying a two-piece bellows strip 66, instead of the one-piece strip 12, to the edge 19 of the body 20. This two-piece bellows strip 66 includes a main strip 67 and a binding or lapping strip 68. The main strip 67 includes a base section 69 and an integral and preferably superposed connector section 70 divided by an offset fold or crease 71. Preferably the connector section 70 is provided with a mar-

ginal section 72 including a rough edge or selvedge folded upon the face of the strip. These details of the main strip 67 may be seen best in Fig. 11. Although the base section may be provided with an infolded marginal edge, to be laid upon the face of the body 20, for economy this is not done. The lapping strip 68 includes a separate piece preferably having infolded marginal sections 73 and 74, when the strip has raw edges or when it is desired to hide the selvedge.

In order to apply this form of strip to a body a modified attachment 75 shown in Fig. 10 is now preferably used. As shown this attachment includes a modified base plate 76 securable to the base 23 in the same manner as the preferred form of attachment 18 already described in detail. A flattened tubular channel 77 is provided to open and guide the main strip 67, as shown in Fig. 10. This channel is similar to the channel 43c of the first form of the invention, differing primarily by not including the contiguous upwardly curled channel 43 which also serves to locate the body 20. Lacking the upwardly curled channel 43h of the preferred form, it is not capable of lapping a marginal section of the main strip 67 around an edge 19 of the body 20. Preferably the channel 77 is provided with a longitudinally extending slot 78 adapted to receive the fold or crease 71 a limited extent to guide the latter and insure an accurate and straight line travel of the main strip 67 through the attachment 75.

To hide the raw edge 19 of the body 20 and edge 79 of the main strip 67 the attachment 75 includes a conventional binder 80 adapted to fold the strip 68 fully around the edges as is clearly apparent in the upper right-hand corner of Fig. 10. This binder receives the lapping strip 68 which is usually made of bias or elastic material, and lays the marginal sections 73 and 74 thereof toward opposite faces of the body 20. The binder is provided with a plate 82 having a screw and slot connection 82' to the base plate 76 so that the binder may be shifted and held in various lateral positions relative to the main channel 77 and base 23. The binder 80 is at its nose end 83 provided with a conventional U-shaped channel (not shown) which effects the final U-shape folding of the strip 68 and also serves to accurately position the edge 19 of the body 20 relative to the strip. Thus, the body 20, strip 67 and strip 68 are accurately brought into registry with each other and guided to the sewing mechanism 22 to be secured with one or both lines of stitching 60 and 61 in very much the same manner as the preferred form hereinbefore described in greater detail.

The base plate 76 may be provided with a cut-out 85 adapted to accommodate the main channel 77 so that a top face 86 thereof is substantially parallel with the top of the base plate to facilitate feeding the body 20 and directing the edge 19 to the binder 80. Preferably this form of attachment 75 is adapted to permit shifting of the main channel 77 into various lateral positions relative to the sewing mechanism, after the base plate 76 is secured to the sewing machine. For this purpose the main channel is provided with one or more fingers 87 fitting into suitable recesses 88 in the base plate 76, and is held in the various desired lateral positions as by a screw and slot connection 89.

The method of forming a bellows pocket or the like with this form of the invention includes the steps of opening the bellows strip 67 so that

a connector section 10 will be in an opened condition instead of a normally superposed condition relative to the integral base section 69; feeding the so-opened bellows strip toward the sewing mechanism; guiding the edge 19 of a body 20 in accurate predetermined relation with the edge 19 of the open bellows strip; lapping a separate binding strip 68 around the edge 19 of the body 20 and edge 19 of the main strip 67; and concurrently sewing the binding strip 68 and the main strip 67 to the body 20 either with one or two lines of stitching. Thus, the present invention provides an economical method of making bellows pockets or the like with an edge finish including two separate strips all in a single handling. After the stitches are completed and as the work moves free of the sewing mechanism the connector section 10 again assumes its superposed position relative to the base section 69.

Variations and modifications may be made within the scope of this invention and portions of the improvements may be used without others.

Having described the invention what is claimed as new is:

1. The method of affixing a prefolded bellows strip divided into superposed base and connector sections by a substantially central crease, to the edge of a body which consists in the steps of opening the connector section relative to the base section; lapping a marginal portion of the base section around an edge of the body; and of stitching the lapped marginal portion at the edge of the body and of concurrently stitching the base section to the body near the crease and along a line spaced from the edge of the body. 35

2. The method of affixing a prefolded bellows strip, divided into superposed base and connector sections by a crease, and a marginal section to a body, comprising the steps of opening the connector section relative to the base section; guiding the opened bellows strip relative to the body; lapping the marginal section around an edge of the body; and of stitching the lapped marginal portion to the body and the base. 40

3. The method of affixing a prefolded main strip, divided into superposed connector and base sections by a substantially central crease, and a binding strip to the edge of a body, which consists in the steps of opening the connector section relative to the base section; guiding a body to the opened strip; lapping a binding strip around an edge of the main strip and edge of the body; and of stitching the lapped binding strip, main strip and body together. 45

4. In a sewing machine for attaching a bellows strip which is folded upon itself to provide superposed connector and base sections and has a marginal section, to a body, the combination of guide means for opening the superposed sections of the strip; a curled section in said guide means for locating an edge of the body and for lapping the marginal section of the strip around the edge of the body; a spring finger associated with the guide means for pressing out the opened sections of the strip; a spring finger in line with the curled section for receiving the folded marginal section and laying it upon a face of the body; an adjustable plate in the first named guide means for confining and guiding bellows strips of various widths in the main guide means; an extension on said guide means for receiving and opening said bellows strip in an inverted condition and for leading it to the main guide at an angle to the longitudinal axis thereof and changing the strip from an inverted to a right-sided position; and

stitching means positioned to secure the bellows strip and body together when the normally superposed connector and base sections of the strip are open.

5. In a sewing machine for attaching a strip which has a marginal section, to a body, the combination of a substantially flat channel guide means having a top and a bottom wall, for receiving the strip and guiding the same at one face 10 of said body; a curled section on said channel guide means for locating an edge of said body and for receiving said marginal section and lapping the same around said edge and over the other face of said body; a yielding finger in line 15 with said curled section, having walls at an angle to each other for enveloping the outside of the lapped marginal section and laying the same on the body; and stitching means adjacent said finger for securing said lapped marginal section 20 and said strip to said body at opposite faces thereof.

6. In a sewing machine for attaching a bellows strip which is folded upon itself to provide normally superposed connector and base sections 25 and has a marginal section, to a body, the combination of a substantially flat channel guide means having a top and a bottom wall, for receiving the bellows strip and maintaining the normally superposed connector and base sections 30 open relative to each other at one face of said body; a curled section on said channel guide means for locating an edge of said body and for receiving said marginal section and lapping the same around said edge and over the other face of 35 said body; yielding means associated with said channel guide means for pressing out said opened connector and base sections, said yielding means overlying said bottom wall and spaced laterally from said curled section; and stitching means for 40 securing said lapped marginal section and said base section to said body at opposite faces thereof.

7. In a sewing machine for attaching a bellows strip which is folded upon itself to provide normally superposed connector and base sections and has a marginal section, to a body, the combination of a substantially flat channel guide means 45 having a top and a bottom wall, for receiving the bellows strip and maintaining the normally superposed connector and base sections open relative to each other at one face of said body; a curled section on said channel guide means for 50 locating an edge of said body and for receiving said marginal section and lapping the same around said edge and over the other face of said body; means spaced laterally from said curled section, for confining said opened connector and base sections in said channel; a spring finger associated with said channel guide means and located between said confining means and said curled section for pressing out said opened 55 connector and base sections; and stitching means for securing said lapped marginal section and said base section to said body at opposite faces thereof.

body; and stitching means including a pair of needles located respectively in line with said curled section and spaced laterally relative to said curled section, for concurrently and respectively securing said lapped marginal section to 5 said body at one face and said base section to said body at the opposite face thereof.

8. In a sewing machine for attaching a bellows strip which is folded upon itself to provide normally superposed connector and base sections and 10 has a marginal section, to a body, the combination of a substantially flat channel guide means having a top and a bottom wall, for receiving the bellows strip and maintaining the normally superposed connector and base sections open relative 15 to each other at one face of said body; a curled section on said channel guide means for locating an edge of said body and for receiving said marginal section and lapping the same around said edge and over the other face of said body; 20 laterally adjustable means in said guide means and spaced laterally from said curled lapping section, for confining and guiding the opened connector and base sections therein; yielding means associated with said channel guide means 25 and located between said curled section and said adjustable means for pressing out said opened connector and base sections; and stitching means for securing said lapped marginal section and said base section to said body at opposite faces 30 thereof.

9. In a sewing machine for attaching a bellows strip which is folded upon itself to provide normally superposed connector and base sections and has a marginal section, to a body, the combination of a substantially flat channel guide means having a top and a bottom wall, for receiving the bellows strip and maintaining the normally superposed connector and base sections open relative to each other at one face of said 40 body; a curled section on said channel guide means for locating an edge of said body and for receiving said marginal section and lapping the same around said edge and over the other face of said body; means spaced laterally from said 45 curled section, for confining said opened connector and base sections in said channel; a spring finger associated with said channel guide means and located between said confining means and said curled section for pressing out said opened 50 connector and base sections; and stitching means for securing said lapped marginal section and said base section to said body at opposite faces thereof.
